UNITED STATES PATENT OFFICE

AURIN E. PAYSON AND MINER P. WETMORE, OF NORWICH, CONNECTICUT
REFRIGERATING DEVICE

Original application filed March 12, 1928, Serial No. 260,870. Divided and this application filed February 26, 1929. Serial No. 342,710.

Our invention is for a self-contained cooling receptacle of novel construction adapted to keep the contents at low temperature. For this purpose we employ a suitable container, preferably a jar of the double-walled vacuum type, provided with a small compartment holding a refrigerating medium. In one embodiment of our invention, this compartment is formed by a double-walled 10 vacuum bottle mounted in the stopper of the receptacle, and the cooling medium is preferably solidified carbon dioxide, commonly known in the market as dry ice. The mouth of the bottle forming the cooling chamber 15 or compartment is closed with a porous cover through which the carbon dioxide gas escapes gradually into the receptacle, where it instantly expands with lowering of temperature. This cover is preferably a porous cup adjustably fitted to expose more or less area for the escape of the refrigerating gas. This enables us to regulate the temperature in the receptacle, as will subsequently be explained more fully. The receptacle is 20 used for storing and dispensing articles (particularly foodstuffs) that must be kept cold. In another form of our invention, the refrigerating unit is supported in the lower portion of the cooling chamber, which may 25 be a double-walled vacuum jar.

The various features and practical advantages of our invention will be fully understood from a detailed description of the accompanying drawing, which illustrate two 30 embodiments of our self-contained refrigerating device. In the drawing—

Fig. 1 represents a cross-sectional view of one form of our invention in which the refrigerating unit is supported at the bottom of a double-walled vacuum jar and is closed by an adjustable porous cup;

Fig. 2 is a transverse cross-section on line 2—2 of Fig. 1; and

Fig. 3 is a fragmentary sectional view of a construction in which the refrigerating unit is contained in the stopper of the jar.

A spherical base 10, preferably of cast metal, has supporting legs 12, which may be cast integral with the base or secured thereto as separate members by suitable fastening

means. This base is provided at the center with a hollow cone-shaped projection 14 which forms a recess 15, for a purpose that will presently appear. A heat-insulated receptacle 16 is firmly supported in upright position on base 10. In the present instance, the receptacle 16 consists of a double-walled vacuum jar of glass, preferably of pyrex glass, or other suitable material. The spherical bottom 17 of the jar fits snugly in the correspondingly shaped body of the supporting base 10. The upper cylindrical portion 10' of the base engages the cylindrical outer wall of the jar 16, so that the latter cannot tilt on the rounded bottom of the base. As these double-walled glass jars have considerable weight, the jar rests firmly in the base without the need of additional fastening means. It is well known that double-walled vacuum vessels have a projecting tip or tubulation through which the chamber between the walls is exhausted. The jar 16 has a projecting tip 18 at the center of its rounded base, and this tip extends into the central recess 15 of base 10, so that the tip is fully protected against injury. In some instances it may be desirable or advisable to place a sheet metal jacket 19 around the jar, as partly shown in Fig. 3. This jacket not only protects the glass jar, but conceals the contents of the same and improves the general outward appearance of the entire device, especially if the jacket is decorated or ornamented with an appropriate design.

Referring to Fig. 3, a disk 22 secured to the underside of a metal cap 23, as by means of an adhesive or in any other practical way, is inserted in the mouth of jar 16. This disk is preferably of cork or other heat-insulating material and engages the inner wall of the jar in a tight frictional fit. The sheet metal cap 23 is provided with a cylindrical flange 24 adapted to fit over the upper end of jacket 19 and engage the same in frictional contact to make a tight yet separable joint. The free edge of flange 24 is slightly turned outwardly, as shown at 25, in order to facilitate the insertion of disk 23 over jacket 19. The cork disk 22 has a central opening 26 for receiving a stopper 27 of cork or similar ma-

terial. The upper end of stopper 27 is formed with a flange 28 adapted to rest on the disk 22. A hollow grip or knob 29, preferably of sheet metal, is attached to the upper end of stopper 27. In the present case, the knob 29 has a flange 30, which is spun or turned into holding engagement with the flange 28 of the stopper. A double-walled vacuum bottle 46 is inserted in the axial opening 32 of stopper 27. The bottle 46 fits so tight in the opening that no additional fastening means is needed. The hollow knob or grip 29 performs the double function of a handle for stopper 27 and a protective casing for bottle 46, which holds a refrigerant diagrammatically indicated by the block 33. At the present time we prefer to use a refrigerant in the form of solidified carbon dioxide, which is popularly known in the trade as dry ice, but any other practical kind of refrigerant or cooling medium may be employed.

The mouth of bottle 46 is closed by a cup-shaped stopper 47, which consists of a material pervious to the passage of gaseous carbon dioxide. The cup 47 is adjustably fitted in bottle 46 so as to expose a predetermined area and thereby regulate the escape of gas. In this way it is possible to control the temperature in jar 16 within a fair range of accuracy. For example, ice cream confections should be kept at about 15° F. above zero to be in nice eatable condition. For yeast cakes, the temperature ought to be about 40° F. above zero. The previous cup 47 can be made of various materials adapted to permit the gradual escape of gas. Among such materials we may mention molded wood pulp, cardboard, unglazed porcelain, porous cement, emery, carborundum, granular compressed cork, solid cork with perforations, leather, cloth mounted on a frame fitting into the bottle, and other materials along the same line.

The operation of the refrigerating apparatus above described will be clearly understood, but it may be summarized in a few sentences. The heat-insulated jar 16 is adapted to hold foodstuffs and other articles that should be kept at low temperature, such as ice cream confections, certain kinds of candies, yeast cakes, and so on. Solidified carbon dioxide or dry ice is packed into the double-walled bottle 46. This so-called dry ice has a temperature of about 114.5 degrees Fahrenheit below zero. As carbon dioxide gas is formed by slow evaporation of the dry ice, the gas escapes through the porous cup 47 into jar 16, where it expands and lowers the surrounding temperature. The rate of evaporation of refrigerant 33 depends on the temperature inside the jar and on the degree of perviousness of cup 47. Obviously, the greater the exposed area of the cup, the faster will the dry ice evaporate. Therefore, by predetermining or regulating

the exposed area of cup 47, it is possible to obtain (within reasonable limits) the desired temperature in receptacle 16. The accumulated expanded gases in the jar pass into the atmosphere when the stopper 27 is removed for access to the contents. The stopper fits in the opening of disk 22 with sufficient looseness to be easily removable, and the opening 26 is big enough to permit the insertion of a hand. It may be advisable to provide a small vent in disk 22 and cap 23 to relieve excessive gaseous pressure in jar 16, in the event of the stopper 27 not being lifted in time to allow the escape of accumulated gas. It should be noticed that the heat-insulated bottle or container 46 prevents the escape of refrigerating gas except through the porous cup 47.

The construction of Fig. 1 differs from that of Fig. 3 mainly in having the refrigerating unit mounted at the bottom of jar 16 instead of in the stopper. The jar 16 of Fig. 1 contains a perforated plate 36 having integral upstanding arms 37 shaped to engage the inner wall of the jar. The upper ends 37' of the arms 37 extend for a sufficient distance along the cylindrical inner wall of jar 16 to lock the plate 36 against lateral movement on the rounded base of the jar. A cylinder 38 is mounted on plate 36 by rivets 39 or the like, and in the chamber 40 of the cylinder is a spring support indicated as a whole by 41. This support rests on the perforated plate 36, and comprises a central disk 42 and spring arms 43 preferably formed integral with the disk. These arms are so shaped that at 44 they engage the cylinder 38 and at 45 they engage the double-walled vacuum bottle 46. When the bottle is inserted between the spring arms 43, the free ends of the latter act like resilient levers held at points 44, so that the bottle is firmly gripped and held in position, and yet is easily removed.

Since the stopper in the bottle of Fig. 1 does not carry the refrigerating unit, it can be of simpler construction than the stopper of Fig. 3. The jar 16 in Fig. 1 is closed at the mouth by a disk 49 of cork, or similar material, attached to the underside of a sheet metal cap 50, which has a cylindrical flange 51 adapted to fit over the jar 16. A vent 52 in disk 49 and cap 50 relieves excessive gaseous pressure in the jar, as more fully explained in connection with Fig. 3. A knob or other finger piece 53 is attached to cap 50 in any practical way. What has been said about the operation of the refrigerating unit in Fig. 3 applies to Fig. 1 without the need of repetition. We need only add that the perforated plate 36 allows the evaporated carbon dioxide to pass into the jar. If desired, a removable dome or cover 48 (perforated or solid) may be mounted on cylinder 38 to protect the refrigerating unit. To replenish the bottle 46, it is withdrawn from the spring

arms 43 together with the stopper cup 47, leaving the supporting parts 36 and 41 in place, but the whole outfit can be taken out if necessary.

6 Although we have shown and described certain specific constructions, it is understood that our invention is not limited to the details set forth. The underlying principles of our new refrigerating device can be mechanically carried out in various other ways without departing from the scope of the invention as defined in the appended claims. This application is a division of our copending case Serial Number 260,870, filed March 12, 1928.

15 We claim as our invention:

1. A refrigerating unit consisting of a stopper adapted to fit into a receptacle and having an axial opening in which a heat-insulated bottle is mounted, said bottle being adapted to contain a refrigerant in the form of solidified gas, and a removable pervious cup closing the mouth of said bottle to permit the gradual escape of gas.

2. A double-walled vacuum jar having its mouth covered by a disk comprising heat-insulated material, said disk having an opening large enough to permit the insertion of a hand, a stopper removably fitted in said opening, said stopper being provided with an opening in which a double-walled vacuum bottle is supported, said bottle being adapted to hold a refrigerant in the form of solidified gas, and a pervious cup closing the mouth of said bottle to allow the escape of gas into the jar.

3. A refrigerating unit consisting of a cork stopper having an axial hole therethrough in which a double-walled vacuum bottle is frictionally held, said bottle being adapted to contain a refrigerant in the form of solidified gas, the mouth of said bottle being at the bottom of said stopper and the base of the bottle extending beyond the other end of the stopper, a hollow knob mounted on said stopper to cover the projecting base of said bottle, said knob also serving as a handle for the stopper, and a pervious cup adjustably fitted in the mouth of said bottle to permit the escape of gas.
